ABSTRACT OF THE DISCLOSURE

This floating nozzle and shroud for a centripetal gas turbine includes an integral nozzle structure having spaced rings connected by circumferentially spaced, angularly disposed vanes, the wall thickness of the rings, vanes and shroud being substantially equal and the structure being loosely arranged in an open annular space between a gas-receiving torus and turbine wheel chamber. The nozzle-receiving space is formed by bolting a combined shroud and exhaust tube to a flange on the frame with spacers therebetween, the bolts and spacers extending through openings formed in the vanes. One ring of the nozzle structure is extended inwardly to form a shroud at the back of the turbine wheel. The loose mounting permits thermally induced expansion and contraction without stress or strain.

Summary

This invention relates generally to turbomachinery and is directed more particularly to a gas turbine engine of the type having a centripetal wheel. Still more particularly, the invention is centered around the mounting of the nozzle and shroud portions of the gas turbine engine, the primary objective being to so support these elements that stress or strain due particularly to expansion and/or contraction resulting from temperature variations will be avoided. The life of the engine will thus be extended.

Heretofore, in engines of this type the nozzle member which is usually of relatively light weight and thin structural section has been rigidly connected to adjacent portions, such as the engine casing or frame, or other parts of heavier construction. All of these parts are exposed to quite high temperatures during engine operation. Such high temperatures cause the parts to expand. When engine operation is discontinued the parts cool. Some parts, such as the nozzle vanes and other adjacent parts of thin section being exposed to cold air since the flame in the combustor has been extinguished, cool rapidly. Other parts which may be of heavier cross section and not directly exposed to the cool air will cool more slowly. With the former parts directly connected to the latter, high stress or strain is introduced which causes the cracking or breaking and premature destruction of the thinner parts. Replacement then becomes necessary.

To avoid the above difficulties, the present construction has been proposed. It includes the features of forming the nozzle integrally and of relatively light construction but mounting it so that it is free from direct or positive connection with adjacent parts of heavier construction. By so supporting the nozzle it is free to expand and contract at different rates than the adjoining elements and may do so

2

without the introduction of stress or strain. When the combustor flame is extinguished and cool air suddenly contacts the nozzle vanes and adjacent structure, contraction thereof can take place without opposition from the still expanded supporting or gas flow confining and directing members.

Another object of the invention is to provide a centripetal gas turbine engine with a nozzle structure having a pair of side rings with gas-directing vanes extending therebetween, and supporting means for the nozzle structure, the supporting means forming a space for relatively loosely receiving the nozzle structure whereby the latter is free to float to a limited extent and expansion and/or contraction can take place without opposition. The mounting obviously prevents such excessive movement of the nozzle structure that the operation of the turbine wheel would be opposed.

Still another object of the invention is to provide a centripetal gas turbine engine with a nozzle, shroud, and gas-receiving torus construction in which one wall of the torus is formed with an opening for the relatively loose reception of a portion of the nozzle and its support, the support also being formed with a space for the relatively loose reception of the nozzle per se, this construction minimizing the possibility of temperature induced expansion and contraction stresses and strains being transmitted from one part to another.

A more specific object is to construct a gas turbine engine having a nozzle construction which includes a pair of integrally formed annular plates spaced by angular vanes, a support member mounted on the engine casing and having a plate to which is bolted one flange of a combined shroud and exhaust gas outlet tube, a plurality of spacers being disposed between the shroud flange and support plate to form a space for the loose reception of the nozzle structure; the space permits limited movement of the nozzle structure to compensate for expansion and contraction caused by wide temperature variations between operating and shutdown conditions of the engine.

Other objects and advantages of the invention will be apparent from a perusal of the following description of one embodiment of the invention illustrated in detail in the accompanying drawings.

Drawings

FIG. 1 is an axial sectional view of a portion of a centripetal gas turbine engine showing the turbine wheel and adjacent nozzle and shroud construction embodying the invention;

FIG. 2 is a vertical transverse sectional view taken through the nozzle mechanism on the plane indicated by the line II—II of FIG. 1;

FIG. 3 is a detail fragmentary sectional view on an enlarged scale taken through a portion of nozzle mechanism and adjacent structure to show one of the nozzle mounting features; and

FIG. 4 is also an enlarged detail sectional view taken on the plane indicated by the line IV—IV of FIG. 3.

Description

More particular reference to the drawing will show that the gas turbine engine selected to illustrate the invention includes a compressor portion A and a turbine portion B. Both of these portions are disposed in an engine casing C formed of a plurality of suitable parts. The casing has spaced bearings 10 and 11 to rotatably

support a shaft assembly 12 to which is suitably affixed a compressor rotor 13 and a turbine wheel 14. This arrangement provides for the rotation of the rotor, the turbine wheel and the shaft as an integral unit.

The casing also supports a shroud 13A for the compressor rotor so that upon rotation of the latter, air is drawn into the passages in the rotor and discharged outwardly from the periphery of the rotor through a diffuser passage 15 to a plenum 16 formed by a part of the casing C. Within the plenum 16 the casing is provided with a gas-receiving torus 17 into which gases resulting from mixing and burning fuel with the compressed air in a combustor (not shown) are discharged. These gases flow through the torus to a nozzle structure 18 formed in accordance with the present invention.

The nozzle structure 18 directs the hot gases against the blades of the turbine wheel to effect rotation of this element and the other parts secured thereto. Nozzle structure 18 includes front and rear annular plates 20, 21 and angularly inclined vanes 22 integrally formed with the plates. The vanes are circumferentially spaced and cooperate with the plates to provide passages through which the gases flow to the turbine wheel. Torus 17 partly surrounds the nozzle structure and a combined peripheral wheel shroud and exhaust tube 23 the outer end of which is secured to the casing as at 24, the torus also having one end wall secured to the casing adjacent the end of tube 23. The other end wall 25 of the torus has an opening formed therein to receive a portion of the nozzle structure. Peripheral wheel shroud 23 has a flange 26 provided with an annular recess 27 to receive the annular front plate 20 of the nozzle structure. It will be noted from FIGS. 2 and 4 that the plates 20, 21 and vanes 22 have openings 28 for bolts 30 employed to secure flange 26 of shroud 23 to a flange 31 formed on a bearing and nozzle support bracket 32 which is in turn secured to the engine casing, as at 33.

The openings 28 also receive elongated spacers 34 the ends of which engage flanges 26 and 31 and serve to limit the spacing therebetween to a distance slightly exceeding the front-to-back measurement of the nozzle structure, i.e., the plates 20, 21 and vanes 22. This construction confines the nozzle structure but permits a predetermined amount of growth both axially and radially of the assembly to accommodate dimensional changes due to temperature variations.

Rear annular plate 21 is extended inwardly, as at 35, to provide a rear shroud for the turbine wheel which is relieved, as at 36, to conform to the shroud. It will be noted that the hub 37 of the wheel terminates immediately within the inner edge of the shroud to inhibit flow of gases to the back of the wheel. By forming rear shroud 35 on plate 21 and disposing it in closely spaced relation to the back edges of the wheel blades, the front surface of the shroud is aligned and substantially faired into the curved surface of the wheel between the vanes. This arrangement guides the hot gases and makes them flow smoothly without interruption from the nozzle through the passages between wheel blades and along the wheel hub. Impingement of the hot gases on the edges of the hub between the blades cannot occur and localized hot spots as a result thereof are prevented.

Attention is called to the fact that the outer surfaces of the plates 20, 21 are relieved to make them of substantially uniform thickness throughout whereby all parts thereof will heat up and cool off at the same rate and therefore will expand and contract uniformly.

In FIG. 3 it will be noted that flange 31 and plate 21 are disposed in the opening in torus end wall 25 which opening is of a size sufficient to permit relative axial movement between the nozzle and shroud assembly and the torus. The wall 25 has a ring 38 bolted thereto to prevent excessive movement in one direction. This ring 38 also partially closes the space between the edge of the opening and the flange 31 to inhibit fluid flow therethrough.

When the gas turbine engine is in operation, compressed air will be received by the plenum 16. This air is supplied to the combustor (not shown) where fuel is mixed therewith and burned to provide hot gases. These gases are conducted by the torus 17 to the nozzle structure 18 which directs them against the turbine wheel blades to rotate the wheel. It will be obvious that the hot gases contacting the nozzle plates and vanes, the shrouds, the exhaust tube, and the wheel will cause the temperatures of these elements to increase, and consequently the elements will expand. By reason of the extra space between flanges 26 and 31 the nozzle structure can expand without opposition. The clearance between the wheel blades and shrouds 23 and 35 is so calculated that no interference to wheel rotation will take place.

When the flow of fuel to the combustor is interrupted to effect a shutdown of the engine, relatively cool compressor discharge air will engage the nozzle structure and adjacent components. This cool air will reduce the temperatures of these elements. Due to the relatively thin wall construction of the nozzle parts they will cool faster and contract more rapidly than the heavier adjacent parts. Once again, it will be obvious that by reason of the floating construction of the nozzle structure the contraction will be unopposed and no stress or strain will be encountered. There will therefore be no cracking, breakage, or other premature failure of these parts. The active life of the engine is thus prolonged.

I claim:

30 1. In a gas turbine engine of the type having a casing, a turbine wheel, and a gas-receiving torus assembly secured to the casing and surrounding such wheel, said torus having an opening in an end wall adjacent the wheel, the combination comprising:

35 (a) nozzle supporting means mounted in said casing and having a ringlike flange substantially closing the opening in the wall of the torus assembly, said supporting means also having a wheel periphery shroud with a flange secured to said ringlike flange in a manner to form a space therebetween;

40 (b) a nozzle assembly disposed for limited movement in the space between said flanges, said assembly being free from direct connection with any adjacent structure and having annular plates integrally formed at the ends of circumferentially spaced angular vanes, said annular plates and vanes being of substantially equal thickness to secure uniform rates of thermal expansion and contraction throughout said nozzle assembly.

45 2. The gas turbine engine nozzle and shroud combination of claim 1 in which said nozzle-supporting means has bolts to connect said ringlike flange and said peripheral shroud flange and spacers adjacent said bolts to provide a nozzle-assembly-receiving space between the flanges.

50 3. The gas turbine engine nozzle and shroud combination of claim 1 in which one of said annular plates is extended radially inwardly to provide a ringlike back shroud for the turbine wheel.

55 4. The gas turbine engine nozzle and shroud combination of claim 1 in which the supporting means is secured to the casing at one side of and in spaced relation from the torus wall having the opening for the supporting means flange, the end wall of the torus opposite that having such opening being attached to the engine casing, and the shroud member adjacent the peripheral portion of the turbine wheel being secured to the engine casing adjacent to the location of attachment of the torus thereto.

60 5. The gas turbine engine nozzle and shroud combination of claim 3 in which the back side of the turbine wheel is shaped to closely fit said shroud with a predetermined amount of clearance space therebetween.

65 6. The gas turbine engine nozzle and shroud combination of claim 3 in which the ringlike shroud at the back

of the turbine wheel is normal to the axis of rotation thereof, the adjacent portion of said wheel being shaped to closely conform to said shroud with a predetermined amount of clearance space therebetween.

7. The gas turbine engine nozzle and shroud combination of claim 3 in which the hub of the turbine wheel terminates adjacent to the inner edge of said ringlike shroud.

8. The gas turbine engine nozzle and shroud combination of claim 2 in which the nozzle plates and some of the vanes are provided with registering openings for the reception of the fastening means employed to connect the flanges of said supporting means and spacing means disposed between the flanges of the peripheral shroud and supporting means to provide limited clearance for said nozzle means.
